UNITED STATES PATENT OFFICE.

WILLIAM A. HATCHER, OF DETROIT, MICHIGAN, ASSIGNOR TO WERNICKE-HATCHER PUMP COMPANY, OF GRAND RAPIDS, MICHIGAN, A CORPORATION OF MICHIGAN.

ROTARY PUMP.

Application filed February 19, 1921. Serial No. 446,470.

To all whom it may concern:

Be it known that I, WILLIAM A. HATCHER, a citizen of the United States, residing at Detroit, county of Wayne, State of Michigan, have invented certain new and useful Improvements in Rotary Pumps, of which the following is a specification.

This invention relates to improvements in rotary pumps.

10 The object of the invention is to provide an improved simplified rotary pump with simplified means of maintaining the cylindrical piston in proper relation to the cylinder.

15 Objects which relate to details will definitely appear from the detailed description to follow.

I accomplish the objects of my invention by the devices and means described in the 20 following specification. The invention is clearly defined and pointed out in the claims.

A structure which is a preferred embodiment of my invention is fully illustrated in 25 the accompanying drawing, forming part of this specification, in which:

Fig. I is an elevation view of a pump embodying the features of my invention.

Fig. II is a vertical longitudinal detail 30 sectional view through a pump embodying the features of my invention, taken on a line corresponding to line 2—2 of Fig. III.

Fig. III is a detail transverse sectional view through my improved pump, taken on 35 a line corresponding to line 3—3 of Figs. I and II.

40 In the drawings the sectional views are taken looking in the direction of the little arrows at the ends of the section lines and similar numerals of reference refer to similar parts throughout the several views.

Considering the numbered parts of the drawing, 1 is the cylinder, having an intake port 2 and an outlet port 3, and supported 45 on any suitable base or flange. 5 and 6 are the cylinder heads. The cylinder head 5 is provided with a hub-like projection 7 having a stuffing box 8 at the end, through which extends the driving shaft 9 which is 50 disposed in a suitable bushing 10 within the said hub 7. A crank pin 11 is at the inner end of the shaft 9, and the end of the shaft is flanged at 12. The crank pin 11 extends into and is journaled in a bushing 13 which 55 is retained and locked in position in the pis-

ton 4 by the longitudinal pin 14. The bushing is provided with a diametrically-disposed horizontal rib 15.

Cylinder head 6 has a hub 16 within which is secured the cap or plug 17 by a suitable 60 cross pin. This cap has a diametrically-disposed vertical rib 18. Disposed between the cap 17 and the end of the bushing 13 is a block 19 having a horizontally-disposed 65 guide slot 15' corresponding to and engaging the rib 15, and a vertically-disposed guide slot 18' engaging the vertical rib 18 of the cap 17. It will thus be seen that when the driving shaft 9 is rotated, the crank pin 11 will carry the eccentric piston 4 around 70 in the cylinder and that it will be maintained in parallel relation thereto by means of the said guide block 19 engaging the transversely-disposed ribs 15 and 18.

Within the cylinder 4 in a radial slot in the 75 piston is disposed a radial vane 20 having lateral projections 21 engaging in transverse slots 22 in the said cylinder heads, after the manner and style of my improved vanes described and claimed in my concurrent patent 80 application Serial No. 446,469, filed Feb. 19, 1921. In this instance the vane is not made adjustable to take up wear and to be self packing. The pump being small and made to handle oil, such adjustable packing feature is unnecessary.

I desire to state that my improved pump can be considerably varied in detail without departing from my invention. I desire to claim the same specifically as well as 90 broadly, as pointed out in the appended claims.

Having thus described my invention what I claim as new and desire to secure by Letters Patent is:

1. In a rotary pump of the class described, the combination of a suitable cylinder with intake and discharge ports, a cylindrical piston therein of less diameter than said cylinder, arranged and disposed in contact with said cylinder, suitable heads for the said cylinder, one of which is provided with a hub and stuffing box, a shaft disposed in said hub with a crank pin at its inner end on which said piston is journaled, a bushing 95 between said crank pin and said piston secured to the said piston and having a diametrically-disposed rib at the end thereof, the opposite head of said cylinder being provided with a cap and having within the same 100 105 110

- a diametrically-disposed rib, a block between said bushing and cap having recesses for the said ribs on opposite faces thereof disposed in planes at right angles to each other, and
- 5 a sliding vane between said piston and said cylinder separating the intake from the discharge, all coacting substantially as described for the purpose specified.
2. In a rotary pump of the class de-
10 scribed, the combination of a suitable cylinder, a cylindrical piston therein of less diameter than said cylinder, arranged and dis-
15 posed in contact with said cylinder, suitable heads for the said cylinder, one of which is provided with a hub and stuffing box, a shaft disposed in said hub with a crank pin at its inner end on which said piston is journaled, a bushing between said crank pin and said piston secured to the said piston and having
20 a diametrically-disposed rib at the end there-
of, the opposite head of said cylinder being provided with a cap and having within the same a diametrically-disposed rib, a block between said bushing and cap having re-
25 cesses for the said ribs on opposite faces thereof disposed in planes at right angles to

each other, intake and discharge ports, and a vane means between said piston and cylinder.

3. In a rotary pump of the class described, 30 a suitable cylinder, a cylindrical piston therein of less diameter than said cylinder arranged and disposed in contact with said cylinder, heads for the said cylinder, a driv-
35 ing shaft journaled in one head with a crank pin at its inner end on which said piston is journaled, a central hub cavity in the oppo-
40 site head, a floating guide block arranged in said cavity with rectilinear guide means on its opposite faces disposed in planes at right angles to each other, and corresponding guides carried by the said piston and said cylinder head for maintaining the relative parallel position of said piston and cylinder when the pump is being driven, as specified. 45

In witness whereof, I have hereunto set my hand and seal in the presence of two wit-
nesses.
